UNITED STATES PATENT OFFICE.

ROY W. WILLIAMS, OF UTICA, SOUTH DAKOTA.

FLOOR-LIFTING DEVICE.

1,343,862.

Specification of Letters Patent. Patented June 15, 1920.

Application filed June 15, 1918. Serial No. 240,125.

To all whom it may concern:

Be it known that I, ROY W. WILLIAMS, a citizen of the United States, residing at Utica, in the county of Yankton and State 5 of South Dakota, have invented certain new and useful Improvements in Floor-Lifting Devices, of which the following is a specification.

This invention relates to improvements in 10 tools and it is the principal object of the invention to provide a novel form of tool for removing flooring from joists and the like in building in a rapid and effectual manner and with but little effort upon part of a user.

15 Other objects will be in part obvious and in part pointed out hereinafter.

In the more detailed description of the invention which is to follow, reference is made to the accompanying drawings, but it will 20 be understood that only one form of the invention is illustrated therein and that various changes and modifications can be made without departing from the spirit or scope of the invention, as defined in the claim.

25 In these drawings:

Figure 1 is a fragmentary perspective of the improved tool, and

Fig. 2 is a vertical longitudinal section therethrough.

30 Referring now more specifically to the drawings, in connection with which like reference characters will designate corresponding parts throughout the several views, 1 represents the head of the improved tool, one 35 side of which is formed with a substantially circular shaped bearing 2 having serrations 3 formed thereon circumferentially for a distance thereof for a purpose which will be hereinafter described. As will be noted, one

40 end of the head 1 is formed with longitudinally disposed spaced arms 4, the upper surfaces of which are slightly curved as at 5, whereby to permit the same to be engaged with boards of flooring in a manner to afford 45 the greatest possible leverage and to permit the boards to be started from the joists with the least possible effort upon part of a user. In this connection, it is to be noted that the circular shaped bearing 2 with serrations 3 50 are arranged adjacent the rear ends of the arms 4 and extend therebetween, to provide a rounded fulcrum for the rolling action of the tool, the serrations serving to provide means for preventing the slipping of the tool 55 when, in use, that is, when the curved bearing surface 2 of the head 1 is engaged with a joist and the arms 4 straddle the same.

An extension 6 is formed on the opposite end of the head 1 and is provided with a tapered socket for receiving the complementally shaped end of a suitable form of handle 7, which handle, as will be understood, can be of any desired length, such as conditions or preference may dictate.

In using the improved tool, the arms 4 65 straddle the joist of the flooring and the rounded bearing 2 thereof engages the marginal portion of the same. Hence, when the tool is rocked, the arms 4 will be moved upwardly into engagement with the underside 70 of the board. As will be noted, the curved intermediate portions of the arms 4 will first engage with the boards and since they are arranged closer to the point of fulcrum than are the outer ends of said arms, a greater 75 leverage will be afforded and as a consequence, the board will be started from its fastening means with but little effort. Slipping of the head of the tool during the rocking of the same is of course prevented by 80 reason of the serrated portions 3 thereof, said portions offering means for assuring a positive connection between the adjacent marginal portion of the joist and said tool. It of course will be understood that various 85 forms of handles can be substituted for the one shown, as may be desired.

As indicated, I do not wish to be understood as confining the invention to the particular embodiment chosen for illustration 90 herein, nor to the exact construction, arrangement and adaptation of parts shown and described, but I reserve the right to make any changes and alterations as fairly fall within the spirit and scope of the invention. 95

A lifting tool comprising an enlarged head substantially circular in cross sectional configuration, a socketed shank formed on the head, longitudinally disposed medially enlarged spaced parallel arms formed integrally with and extending from the head, the curved surface of the head between and beneath the arms being serrated to provide a gripping portion, and the curved surface of the head above the arms being unbroken to provide an abutment for an object acted upon.

In testimony whereof, I affix my signature hereto.

ROY W. WILLIAMS.
